UNITED STATES PATENT OFFICE

EDWIN T. LORIG AND ROLLAND E. PETERSON, OF GARY, INDIANA, ASSIGNEES TO
AMERICAN SHEET AND TIN PLATE COMPANY, A CORPORATION OF NEW JERSEY

CONVEYER CONTROL MECHANISM

Application filed August 29, 1930. Serial No. 478,747.

This invention relates to conveyor control apparatus, and while not limited thereto, relates more particularly to control apparatus for controlling the operation of the conveyors in tin mill pack heating furnaces and the like and has for one of its objects the provision of such control apparatus which is in part automatic and in part manually operated, and which is provided with means for positively preventing the overrun and premature discharge of the conveyed packs or other material.

Another object is to provide a control of this class which is composed of few parts, is durable and specially adapted for heavy duty use such as it will receive in steel mill practice.

In the drawings:

Figure 1 is a transverse section through the discharge end of a furnace having our invention applied thereto.

Figure 2 is an end elevation of the control mechanism.

Figure 3 is a diagram of the control circuits.

Referring more particularly to the drawings, the numeral 2 designates the furnace as a whole which is provided with the usual transverse conveyor rollers 3 which are adapted to be driven by any of the several usual combinations of mechanisms powered by the motor 4 (indicated in the wiring diagram of Figure 3).

A control shaft 5 extends transversely of the furnace above the conveyor rollers 3 at the discharge end of the furnace and is journaled in bearings 6. The shaft 5 is preferably water-cooled to prevent warping.

A multiple pronged trigger member 7 is keyed to the shaft 5 and has its prongs 8 normally extending down between the disks 9 on the rollers 3 so as to be in the path of travel of the packs or other material being conveyed.

The shaft 5 is connected by a flexible coupling 10 to a shaft 12 journaled in bearings 13. A cam 14 is keyed or otherwise fixed on the shaft 12 and serves to operate a two-way limit switch 15 of standard design.

A solenoid 16 is mounted on a bracket 17

above the shaft 12 and has its plunger 18 provided with an extension 19.

The plunger extension 19 is cut away, as at 20, to provide an opening in which an arm 21, which is keyed to the shaft 12, is adapted to swing. A square stop shoulder 22 is formed within the cut-away portion of said plunger extension and is adapted to be engaged by a lug or jaw 23 on the arm 21 when the arm is rotated.

A pair of links 24 are pivotally connected at one end to the arm 21 and have their other end pivotally mounted on a pin 25 which is slidably mounted in a slot 26 in the plunger extension 19 so as to permit a limited free movement of said shaft 12, arm 21, and links 24 relative to said plunger extension.

The operation will be described in connection with the wiring diagram of Figure 3. With the control mechanism in the positions shown in the drawings, the motor 4 is energized to rotate the conveyor rollers 3 and convey a pack of sheets or other material through the furnace. As the material strikes the trigger 7, the trigger will be forced to swing forwardly so as to rock the shafts 5 and 12 sufficiently to cause the cam 14 to actuate the limit switch 15. Actuation of the limit switch 15 by the cam 14 will break the circuit to the motor 4.

When the pack of sheets or other material strikes the trigger 7, so as to rock the shafts 5 and 12, the amount of movement is limited by the jaw 23 on the arm 21 engaging the stop shoulder 22 within the cut-away portion 20 of the plunger extension 19. The links 24 move freely relative to the plunger extension during the rocking of the trigger due to the mounting of the pivot pin 25 in the slot 26. The engagement of the jaw 23 with the shoulder 22 forms a positive lock which prevents further movement of the trigger 7 and thereby prevents overrunning or accidental discharge of the packs.

When the operator desires to discharge the material previously moved against the trigger 7 he will depress a foot treadle switch 30 to complete an energizing circuit through the solenoid 16 and through the motor 4, thus causing the plunger 18 and extension 19 of

the solenoid to move vertically to release the jaw 23 from the shoulder 22 and to rock the shafts 5 and 12 a sufficient amount to permit free movement of the pack of sheets or other material thereunder, and at the same time the motor 4 again operates to drive the conveyer rollers to feed the material forward out of the furnace.

When the pack of sheets or other piece of material is discharged the operator will release the treadle switch 30 and thereby break the energizing circuit to the solenoid 16 so that the plunger 18 and its associated parts will return to normal position, thus the trigger 7 and switch 15 will be returned to normal position. The motor 4 will continue to run until another pack of sheets strikes the trigger 7 and opens the switch 15.

While we have shown and described one specific embodiment of our invention it will be understood that we do not wish to be limited thereto since it may be adapted for use with various types of roller conveyers and various types of conveyer or continuous furnaces, and various modifications may be made without departing from the scope of the invention, as defined in the appended claims.

We claim:

1. The combination with a motor-driven roller conveyer, of means for controlling the operation of said conveyer rollers, said means comprising a shaft journaled in suitable bearings and extending parallel with said conveyer rollers at a distance above said rollers, at least one trigger member fixed on said shaft and extending downward into the path of travel of the material being conveyed by said rollers, power means for rotating said shaft to move said trigger member out of the path of travel of the material on said conveyer rollers, means for permitting a slight rotation of said shaft when the material engages said trigger, means operable by said slight rotation of said shaft for deenergizing the driving motor for said conveying rollers, and manually operated means for simultaneously energizing said power means for rotating said trigger carrying shaft and said conveyer roller motor to permit the discharge of the material previously held by said trigger.

2. The combination with a motor-driven roller conveyer, of means for controlling the operation of said conveyer rollers, said means comprising a shaft journaled in suitable bearings and extending parallel with said conveyer rollers at a distance above said rollers, at least one trigger member fixed on said shaft and extending downward into the path of travel of the material being conveyed by said rollers, a power-operated plunger for rotating said shaft, means forming a loose connection between said shaft and said plunger whereby said shaft may have a limited free movement, said shaft being

adapted to be rotated within the limits of its free movement when the material engages said trigger, means operable by said free movement of said shaft for deenergizing the driving motor for said conveying rollers, and manually operated means for simultaneously energizing said power-operated plunger for rotating said trigger carrying shaft and said conveyer roller motor to permit the discharge of the material previously held by said trigger.

3. The combination with an electric motor-operated roller conveyer, of means for controlling the operation of said conveyer, said means comprising a shaft journaled in suitable bearings and extending parallel with said conveyer rollers at a distance above said rollers, at least one trigger member fixed on said shaft and extending downward into the path of travel of the material being conveyed by said rollers, a second shaft flexibly coupled to said first named shaft, a solenoid, a lever keyed to said second shaft, a link connection between said lever and the plunger of said solenoid, said link connection having a loose connection with the plunger of said solenoid to permit a limited free movement of said link relative to said solenoid, said shafts being adapted to be rotated within the limits of the free movement of said link connection when the material being conveyed engages said trigger, means operable by the free movement of said shaft for deenergizing the driving motor for said conveying rollers, and manually operated means for simultaneously energizing said solenoid to rotate said shafts and said conveyer roller motor to permit the discharge of the material previously held by said trigger.

4. The combination with an electric motor-operated roller conveyer, of means for controlling the operation of said conveyer, said means comprising a shaft journaled in suitable bearings and extending parallel with said conveyer rollers at a distance above said rollers, at least one trigger member fixed on said shaft and extending downward into the path of travel of the material being conveyed by said rollers, a second shaft flexibly coupled to said first named shaft, a solenoid, a lever keyed to said second shaft, a link connection between said lever and the plunger of said solenoid, said link connection having a loose connection with the plunger of said solenoid to permit a limited free movement of said link relative to said solenoid, said shafts being adapted to be rotated within the limits of the free movement of said link connection when the material being conveyed engages said trigger, means for positively limiting the free movement of said shafts, said means including a lug on said lever adapted to engage the plunger of said solenoid, means operable by the free movement of said shaft for deenergizing

the driving motor for said conveying rollers, and manually operated means for simultaneously energizing said solenoid to rotate said shafts and said conveyer roller motor to permit the discharge of the material previously held by said trigger.

5 In testimony whereof, we have hereunto set our hands.

EDWIN T. LORIG.
